SIEGMUND LOEWE, OF BERLIN, GERMANY

INCANDESCENT WIRE ARRANGEMENT IN AUDIONS

Application filed February 19, 1929, Serial No. 341,143, and in Germany February 22, 1928.

As the incandescent wires in audions considerably expand under the influence of heating during operation, the possibility arises of their being bent. This possibility is particularly strong if the filaments are exposed to mechanical vibration of the valve. The bends frequently are not constant but variable and as a consequence vibrations of the filament take place which may cause disturbances; as an example the reciprocal of the amplification factor (especially the electrostatic action of the anode through the grid upon the cathode) may undergo a periodical variation. In this manner the amplification factor varies with the frequency and disturbing amplitude-oscillations of the plate current and plate voltage respectively occur which more particularly lead to disagreeable interfering noises if they possess the period of an audible frequency.

These disturbances are by themselves not changed if, as is frequently done, two filaments are laid out in parallel. Fig. 6 shows one of the known arrangements consisting of an incandescent wire 1 whose leads 2 and 3 are on the same side of the electrode system whilst on the other side it is borne and strained in the middle by a support 4, so that two filament stretches 1' and 1'' run inside the electrode system acute-angled to one another.

The invention consists in restricting in a particular manner several filaments in their possibilities of movement and expansion towards one another in such a manner that the interfering oscillations above described are either altogether prevented or considerably reduced in their amplitude or may occur only in such direction that they do not cause disturbances.

My invention may be best understood with reference to the accompanying drawings.

Fig. 1 shows a cross-section by an electron discharge device with the incandescent wire arrangement according to my invention.

Fig. 2 shows the way of manufacturing the incandescent wire arrangement of Fig. 1.

Fig. 3 shows a modification of the incandescent wire arrangement of Fig. 1 in a larger scale, the manufacturing of which is illustrated in Fig. 4.

A further modification of mechanical means for tightening the incandescent wires is illustrated in Fig. 5.

Fig. 6 shows as above mentioned the known arrangement having disadvantages to be avoided according to my invention, particularly to the arrangement of Fig. 1.

Fig. 7 is a modification of my device in side elevation.

Fig. 8 shows a modification of the filaments inside of the electrode system.

Figs. 9-11 relate to incandescent wire arrangements with more than 2 filaments.

Fig. 1 shows an especially simple embodiment of an arrangement of two incandescent wires where the possibilities of oscillation are limited according to the invention. For this purpose two filaments 1 and 2 need only be laid one above the other in such a manner that they cross, say, at the central point 5. In the course of manufacture this is appropriately done in such a manner that two wires are first laid out in parallel at which according to Fig. 2 the supporting wires 3 and 4 are arranged in the same directions and that, in order to effect the arrangement according to Fig. 1, one of these supporting wires, for instance wire 4, is turned by 360° or appropriately somewhat more. There is no objection to producing the arrangement in such a manner that both supporting wires 3 and 4 lie at the different sides of the parallel filaments 1 and 2 and that one of the supporting wires is turned by fully 180° so that the wires are interlaced.

The electron discharge device of Fig. 1 is in a well known manner completed by the grid 6, the plate 7, the bulb 8, the socket 9.

A wire arrangement as shown in Figs. 1

and 3 respectively is no longer in a position to carry out lateral oscillations even if the filaments expand very strongly; the possibility of deflection and oscillation within the area drawn more particularly has been limited or even made impossible. Such arrangements of filaments are particularly suitable for such arrangements of electrodes in which a deflection in a certain direction does not exercise a disturbing influence. Fig. 8 shows such an arrangement consisting of parallel level anode plates 10 and 11 and grids 12 and 13 where the common plane of the filaments 1 and 2 is vertical to the anode planes. Even if such an arrangement should still carry out oscillations parallel to the anodes 10 and 11 in the direction of the double arrow, this would not effect a change in the reciprocal of the amplification factor of the electrode system. The disturbances above described therefore could not occur notwithstanding any oscillations of the filament.

The form of construction according to Fig. 3 appears to be the simplest for the mutual stiffening arrangement of two filaments. It may happen, however, that such arrangements have electrical drawbacks of another nature. In many cases an unfavourable influence might be exerted on the course of the valve characteristic if according to Figs. 1 and 3 respectively the central point of the filaments, constructed as a junction, would have a larger distance from the other electrodes than the other parts. If that is to be avoided, a clasp 14 may in the manner shown in Fig. 5 be laid round the middle portion of filaments 1 and 2 in order thus to connect the same.

Figs. 1 and 5 relate to leads of the filament voltage in which the full difference of voltage exists between the right ends of the filament and the left ends so that the middle point 5 according to the invention lies simultaneously for the two filaments at the same potential even if the filament voltage switched on is not constant, but an alternating voltage.

If, however, in the manner shown in Fig. 6, the full filament voltage lies between neighbouring ends of the filaments, a conductive connection of the middle points of the filaments would lead to disturbances of the desired course of the current.

In filament arrangements in which middle points of the filaments which are lying opposite one another, do not possess the same potential, it is advisable according to the further subject of the invention, to arrange separators, either by a small tube or disc of insulating material 15 being according to Fig. 7 laid between the filaments which otherwise, according to Figs. 1 and 3 are interlaced, or jointed by the clasp 14 of Fig. 5.

65 The further subject of the invention re-

lates to filament arrangements which even in the case of electrodes of any shape not only neutralize such vibrations, but fully avoid the same.

For this purpose more than two incandescent wires are used, for instance three incandescent wires interlacing in similar manner as the two filaments of Figs. 1, 3, 5, 8, 7. In that case there is in no direction as essential possibility of the filament bending through and therefore of a disturbing oscillation.

Figs. 9 and 10 illustrate an exemplary embodiment of the further subject of the invention. In order to make the matter plainer only three filaments are used though the invention may not only be applied also, but may even be better realized if a larger number of filaments is used. In Fig. 9 three filaments 16, 17, 18 are strained in parallel and clamped together by a clasp 19 in order that they may not deflect sidewise. In Fig. 10 the three incandescent wires 16, 17 and 18 meet at a junction 5. This may be accomplished, for instance, by the incandescent wires being first held parallel to one another whereat the points for fixing the three filaments appropriately lie on each side at the corners of an equilateral triangle 20 and 21 so that the two equilateral triangles run in parallel planes to one another. If, now, one of the two triangles is within its plane turned sufficiently wide round its centre, appropriately by 180° or more, the filaments touch one another or upon further turning interlace. In Fig. 10 the angle of rotation is 360°. Such stabilized filament arrangement cannot be bent through in any direction with the normally appearing forces.

If more than three filaments are used it is also advisable to fix the ends of the filaments to the corners of a regular polygon, in order that for reasons of symmetry no direction is preferred for a deflection or bending.

Fig. 11 shows a cross-section of a filament arrangement according to Fig. 9 or 10 with cylindrical grid 22 and anode 23.

With the use, too, of more than 2 incandescent wires it may be advisable to interpose insulations between the wires whose contact points lie at different potentials.

An arrangement, moreover, where only a small number (say 2) of filaments are used, may be given the bending stability of an arrangement with a larger number of incandescent wires by using wires with non-circular cross-section in order that the moment of inertia of the wire cross-section is largest in the direction in which a certain possibility of deflection still exists.

If, according to the forms of construction of Figs. 5 and 7 special substances are arranged between the filaments, for instance in the shape of the connecting clasp 17 or a disc or small plate 15 of insulating material, it is advisable according to the further sub-

ject of the invention that these substances should be given such dimensions that in consideration of the elasticity of the connected filaments no natural vibrations of disturbing frequency and amplitude result.

5 I claim:

1. Method for manufacturing incandescent cathode arrangement in an electron discharge device using several filaments having a common crossing point, which consists in arranging the single filaments in parallel, in connecting the corresponding ends of said filaments by means of metallic conductors, in turning one of said metallic conductors in order to produce a mechanic crossing of said filaments.

2. Method for manufacturing incandescent cathode arrangements in an electron discharge device using three filaments having a common crossing point, which consists in arranging the single filaments in parallel, in connecting the corresponding ends of said filaments by means of metallic conductors, and in turning one of said metallic conductors in order to produce a mechanic crossing of said filaments.

3. Method for manufacturing incandescent cathode arrangements in an electron discharge device using more than two filaments having a common crossing point, which consists in arranging the single filaments in parallel, in fastening the ends of said filaments in the corners of regular polygons manufactured of conductive material, and in turning one of said polygons in order to produce a mechanic crossing of said filaments.

4. Method for manufacturing incandescent cathode arrangements in an electron discharge device using three filaments having a common crossing point, which consists in arranging the single filaments in parallel, in fastening the ends of said filaments in the corners of regular triangles manufactured of conductive material, and in turning one of said triangles in order to produce a mechanic crossing of said filaments.

5. Method for manufacturing incandescent cathode arrangements in an electron discharge device using three filaments having a common crossing point, which consists in arranging the single filaments in parallel, in fastening the ends of said filaments in the corners of regular triangles of wire, and in turning one of said triangles in order to produce a mechanic crossing of said filaments.

6. Method for manufacturing incandescent cathode arrangements in an electron discharge device using more than two filaments having a common crossing point, which consists in arranging the single filaments in parallel, in fastening the ends of said filaments in the corners of regular polygons manufactured of conductive material, and in turning one of said polygons in order to produce a mechanic crossing of said fila-

ments, in supplying each polygon with a leading-in wire for the heating current.

7. In an electron discharge device an incandescent cathode arrangement consisting of several filaments having a common crossing point, of regular polygons of conductive material at which the ends of said filaments are fastened, of leading-in wires of said cathode arrangements attached at said regular polygons, of a grid, of an anode, and of leading wires of said electrodes.

In testimony whereof I have affixed my signature.
